UNITED STATES PATENT OFFICE.

JOSEPH SUSTARICH, OF CHICAGO, ILLINOIS.

POWER HAMMER.

Application filed October 6, 1921. Serial No. 505,854.

To all whom it may concern:

Be it known that I, JOSEPH SUSTARICH, a citizen of the United States of America, residing at Chicago, in the county of Cook 5 and State of Illinois, have invented certain new and useful Improvements in Power Hammers, of which the following is a specification.

This invention relates to certain new and 10 useful improvements in power hammers employed in the art of metal forging and welding.

The primary object of the invention is to provide a generally simplified and improved 15 means for attaching the hammer to the helve of that type of press or power hammer embodying a vertically slideable and guided hammer.

Another object of the invention is to provide an improved and yielding means for 20 connecting the sliding hammer and swinging helve of a power press allowing ready change in the angular relations of the hammer and helve.

Still another object of the invention is to provide an improved attaching means for 25 connecting the hammer and helve of a power press which may be quickly applied or removed for repair or renewal purposes and 30 at a reasonable cost and expenditure of time and labor.

Other objects will appear as the nature of 35 the invention is better understood and the invention consists in the novel form, combination and arrangement of parts herein- 40 after more fully described in connection with the accompanying drawings and in which like designating characters refer to corresponding parts throughout the several views.

In the drawings,

Figure 1 is a side elevational view of a 45 power hammer constructed in accordance with the present invention,

Figure 2 is a front elevational view thereof,

Figure 3 is an enlarged front elevational view of the hammer attaching yoke,

Figure 4 is a top plan view of the device 50 shown in Figure 3,

Figure 5 is a side elevational view of the device shown in Figure 3,

Figure 6 is a vertical sectional view taken 55 on line VI—VI of Fig. 2, and

Figure 7 is a vertical sectional view taken on line VII—VII of Fig. 1.

Referring more in detail to the several views, the present invention is shown as incorporated in a press including the usual bed 5 with an intermediate upright or standard 6 having a transverse shaft 7 journaled in the upper end thereof upon which one end of the helve 8 is secured, said shaft 7 being extended to one side of the standard where one end of a lever 9 is secured thereon. 60 The other end of the lever 9 is connected in the usual way by a pitman 10 to a crank pin 11 rigid with a fast pulley 12 that is fixed upon a transverse driving shaft 13 journaled at the rear end of the bed 5, another pulley 14 being employed upon the shaft 13 and freely revoluble upon said shaft for convenience in throwing the hammer into and out of operation. The machine is provided with a separate bolted-on anvil 70 block 15 at its forward end which is overhung by an upwardly and forwardly curved standard 16 having a guide portion 17 in which the weighted hammer 18 is vertically slideable. The anvil block 15 and hammer 75 18 are provided with the usual removable dies 19 and the guide portions 17 may be provided with suitable wearing plates with adjustment screws 20 as is usual in the art. 80

The present invention resides particularly in the means for connecting the upper end of the hammer 18 to the forward or free end of the helve 8. The present invention aims to provide a serviceable means for this purpose which will permit swinging 90 of the helve without binding of the hammer within its guide as the angular relation between the helve and hammer vary in operation. The helve 8 is provided at its free end portion with a depending enlargement 21 95 having an arcuate under surface, and a transverse semi-circular groove 22 is provided in the upper surface of the helve concentric with the arcuate face of the enlargement, the central portion of said groove 22 100 being deepened as at 23 for a purpose which will presently become apparent.

A transverse cross head 24 is seated in the groove 22 so as to freely rotate in the latter, and the central portion of this cross head is 105 provided with an annular enlargement 25 arranged to be received within the deepened portion 23 of the groove 22 so as to hold the cross head 24 against movement transversely of the helve. The reduced upper end of 110 the hammer 18 is provided with a transverse opening 26 through which extends a

saddle plate 27 of curved form, the ends of the saddle 27 being bifurcated to provide pairs of legs 28 of upwardly curved form which extend beyond opposite sides of the hammer 18. A T-head bolt 29 is disposed at each side of the helve with its head portion engaged under the curved or hook-shaped legs 28 and with its shank extending upwardly through the slot or space between said legs, said bolts 29 being slidably extended through transverse openings provided in projecting end portions 30 of the cross head 24. The upper and lower faces of the ends 30 of the cross head 24 are preferably flat and washers 31 are disposed upon the flat upper faces thereof to form abutments for the lower ends of the helical springs 32 which surround the shanks of the bolts above the cross head, the upper ends of said springs bearing against further washers 33 placed upon the bolts and removably held in position by means of nuts 34 or the like threaded upon the upper ends of said bolt shanks. The hammer 18 is provided with a bearing plate 35 upon its upper end with a concave upper surface fitting and slidably engaging the arcuate surface of the depending enlargement 21, and contact between these two surfaces is maintained by means of the springs 32 urging the bolts 29 upwardly together with the saddle 27.

In operation, the helve 8 is allowed to lower for causing movement of the hammer and its die toward the die block and as this takes place, the angular relation of the hammer and helve is changed, such change being permitted by swinging movement of the bolts 29 relative to the helve at which time the cross head 24 rotates partially in the groove 22 and the bearing plate 35 slides forwardly on the depending enlargement 21. In the initial lifting operation of the helve 8, the operating mechanism is cushioned to a certain extent by the springs 32 and then the reverse swinging of the bolts 29 takes place under the yielding action of the springs 32.

It will be seen that the means for attaching the hammer to the helve substantially involves a U-shaped yoke 27, 29 having a part extending through the hammer and having a spring pressed sliding cross head 24 pivotally mounted transversely of the helve and urged by springs into engagement with the upper surface of the helve. Also, it will be seen that this connection is composed of a number of separable yet durable parts which may be cheaply and easily manufactured as well as placed into use and which will efficiently serve the function for which it is intended.

From the foregoing description, it is believed that the construction and operation as well as the advantages of the present invention will be readily understood and appreciated by those skilled in the art.

Minor changes may be made in the invention without departing from the spirit and scope of the same, as claimed.

What is claimed as new is:

1. In a power hammer wherein a helve is provided and mounted for vertical swinging movement and wherein a hammer is slidably guided for vertical movement adjacent the free end of the helve, a yoke extending through said hammer and upwardly along opposite sides of the helve, and a transverse cross head slidably mounted upon the yoke above the helve and pivotally mounted transversely in the upper surface of the latter. 70

2. The combination with the vertically swinging helve of a power hammer having a transverse groove in the upper surface of the free end thereof and a vertically 75 slideable and guided hammer disposed beneath said free end of the helve, of a yoke having its intermediate portion extending through the hammer and its legs extending upwardly along opposite sides of the helve, and a cross head slidably mounted upon the 80 legs of the yoke and journaled in said transverse groove.

3. The combination with the vertically swinging helve of a power hammer having a transverse groove in the upper surface 95 of the free end thereof and a vertically slideable and guided hammer disposed beneath said free end of the helve, of a yoke having its intermediate portion extending through the hammer and its legs extending 100 upwardly along opposite sides of the helve, a cross head slidably mounted upon the legs of the yoke and journaled in said transverse groove, nuts upon the upper ends of said yoke legs, and compression springs surrounding the legs of the yoke between the cross head and said nuts. 105

4. The combination with the vertically swinging helve of a power hammer having a transverse groove in the upper surface of the free end thereof and a vertically 110 slideable and guided hammer disposed beneath said free end of the helve, of a yoke having its intermediate portion extending through the hammer and its legs extending upwardly along opposite sides of the helve, a cross head slidably mounted upon the legs of the yoke and journaled in said transverse groove, nuts upon the upper end of said yoke legs, compressed springs surrounding 115 the legs of the yoke between the cross head and said nuts, the intermediate portion of the yoke which extends through the hammer comprising a saddle with bifurcated ends forming a pair of upwardly curved legs at 120 each end of the saddle, and the legs of said yoke including T-head bolts with the heads of the same engaged under the bifurcated ends of the saddle. 125

5. The combination with the vertically 130

swinging helve of a power hammer having a transverse groove in the upper surface of the free end thereof and a vertically 5 slideable and guided hammer disposed beneath said free end of the helve, of a yoke having its intermediate portion extending through the hammer and its legs extending upwardly along opposite sides of the helve, a cross head slidably mounted upon the legs 10 of the yoke and journaled in said transverse groove, nuts upon the upper ends of said yoke legs, compression springs sur-

rounding the legs of the yoke between the cross head and said nuts, said helve being provided with a depending enlargement 15 with an arcuate convex lower surface concentric with said transverse groove, and a bearing plate fitting and slidably engaging said arcuate surface and carried upon the upper end of the hammer. 20

In testimony whereof I affix my signature.

JOSEPH SUSTARICH.
